UNITED STATES PATENT OFFICE.

ROLLO M. VICK, OF ALLIANCE, OHIO.

CREDIT-CABINET.

No. 890,109.

Specification of Letters Patent.

Patented June 9, 1908.

Application filed September 23, 1907. Serial No. 394,112.

To all whom it may concern:

Be it known that I, ROLLO M. VICK, a citizen of the United States, residing at Alliance, in the county of Stark and State of Ohio, have invented certain new and useful Improvements in Credit-Cabinets; and I do hereby declare that the following is a full, clear, and exact description of the same, reference being had to the accompanying drawing, making a part of this specification, and to the numerals and figures of reference marked thereon, in which—

Figure 1 is a perspective view showing the cabinet frame partly broken away and showing some of the credit leaves lowered. Fig. 2 is a view showing the credit leaf supporting base and illustrating the credit leaf counterbalance contact arms in proper relationship with said base, also showing a portion of the frame. Fig. 3 is a vertical section of a portion of the cabinet frame, showing the leaves and counterweights properly located with reference thereto. Fig. 4 is a view showing a portion of one of the credit leaves and illustrating a credit slip holding clip connected thereto. Fig. 5 is an edge view of the credit slip holding leaves showing the same spaced in their relative position when the same are located in the cabinet frame. Fig. 6 is a view showing the credit slip holding leaves nested and in position to be placed in a safe or other receptacle. Fig. 7 is a vertical section of a portion of one of the credit slip holding leaves illustrating the slotted spacing and holding plate in the position shown in Fig. 6 and the catch spring in position to hold the slotted plate in the position illustrated in Fig. 6.

The present invention has relation to credit cabinets, and it consists in the novel arrangement hereinafter described and particularly pointed out in the claims.

Similar numerals of reference indicate corresponding parts in all the figures of the drawing.

In the accompanying drawing, 1 represents the cabinet frame or casing, which may be of the form shown or it may be of any other desired form reference being had to the arrangement and location of the different parts hereinafter described. To the casing 1 is connected the credit leaf supporting base or plate 2, said plate being located substantially as shown and as shown it is inclined upward from its front or forward edge to its rear edge and

is so inclined for the purpose hereinafter described. The credit slip holding leaves 3 are substantially of the form shown and are preferably provided with the end flanges 4, which end flanges are connected to the leaves 3 in any convenient and well known manner. To the bottom or lower ends of the various credit slip holding leaves 3 are attached the rods 5, which rods are formed of a length somewhat greater than the width of the credit slip holding leaves or in other words the rods are extended beyond the ends of the credit slip holding leaves.

In the drawings I have illustrated the rods 5 as extended entirely across the bottom edges of the credit slip holding leaves, but this is not absolutely necessary as the objects and purposes hereinafter described can be carried out equally as well by means of short rods or pins connected to the ends of the various leaves 3. At the ends of the various credit slip holding leaves are located the slotted plates 6, which slotted plates are preferably formed tri-angular and are so formed for the purpose hereinafter described.

The plates 6 are provided with a series of slots 7 through which slots the rods 5 are passed and said rods provided with the heads 8, which heads are located upon the outer sides of the plates 6, by which arrangement said slotted plates are properly connected to the various credit slip holding leaves 3. To the inclined base or support 2 are pivotally attached a series of bars 9, which bars are extended upward any desired distance above the top and below the base or support 2. To the portions of the bars 9 extended below the base or support 2 are attached the counter weights 10, which counter weights are adjustably connected by screw threads formed upon the bars 9. In use when it is desired to place the credit leaves in position with reference to the credit cabinet frame the leaves are set upon the base 2 as best illustrated in Fig. 1 and the slotted plates 6 brought into the position illustrated in said Fig. 1 by which arrangement the credit slip holding leaves are spaced from each other, and by reason of the leaves resting upon the inclined base and the slotted plates 6 being held against downward movement by the rods 5 engaging the tops or upper ends of the slots 7, said leaves will be spaced apart a distance somewhat greater than the distance between the slots 7, thereby providing for the

100
105
110

free movement of each credit slip holding leaf as it is brought into the lowered position or returned to an elevated one. It will however be understood that it is not necessary 5 that the rods 5 engage the top ends of the slots 7, except to hold the plates 6 against downward movement, owing to the fact that said plates are pivotally connected to the rod 5 or its equivalent connected to the front 10 or forward credit slip holding leaf. When any given credit slip holding leaf is brought into a lowered position the bars 9 will turn upon their pivotal points, which in this instance are the pins 11, which pins rest upon 15 the top of the base 2 and held in position by means of the staples 12; but any other means may be employed for pivotally connecting the bars 9 to the base or support 2 as the only 20 object is to provide pivotal connection for the bars 9.

For the purpose of providing a counter balance for each credit slip holding leaf the bottom or lower ends of said bars are provided with the weights 10, which weights are 25 brought into an elevated position when the leaves are lowered and for the purpose of preventing any interference of the movement of the various weights 10, the bars 9 are located as illustrated in Fig. 2, that is to say 30 the bars are not in direct alinement with reference to each other, thereby providing room for the various weights to pass each other during their movements.

For the purpose of holding the bottom or 35 lower edge of each credit leaf out of direct contact with the base or support 2 the various rods 5 are provided with the rollers 13, which rollers may be securely attached to the rods 5 or they may be loosely mounted 40 thereon if desired. By providing the rollers 13 the leaves are free to be turned into a lowered position or brought into an elevated one, and by providing the slotted plates 6 and extending the rods 5 through the slots 45 each credit slip holding leaf is held in proper spaced relationship with reference to each other, thereby permitting any desired number 50 of leaves to be brought into a lowered position at one time or any single leaf as may be desired from time to time.

It is well understood that in use the credit slip holding leaves carry credit slips, which credit slips are held by means of the clips 14, and owing to the fact that the number of 55 credit slips vary from time to time the weights 10 are adjustably connected to the bars 9 thereby providing a means for bringing the weights to or from the pivotal points of the bars to which the weights are attached. The 60 weights 10 should be somewhat lighter than the combined weight of the credit slip holding leaves, the clips, and the credit slips; the difference between the weight of the credit slip holding leaves and the weights should be 65 such that adjustment of the weights is seldom

required and only required when a large number of credit slips are placed in position and carried by the credit slip holding leaves. When it is desired to remove the credit slip holding leaves together with the credit slips carried by the credit slip holding leaves, said credit slip holding leaves and slotted plates 6 are lifted from the support or base 2 after which the credit slip holding leaves can be placed in the position illustrated in Fig. 6, or in other words all of said credit leaves brought into alinement at their bottom and lower edges and the triangular plates 6 placed in the position illustrated in Fig. 6 and held in that position by means of the spring catch 75 15 engaging the top or upper wall of one of the slots 7 as best illustrated in Fig. 7.

It will be understood that when the plates 6 are brought into the position illustrated in Fig. 6 and the lower ends of the credit slip holding leaves brought into proper alinement they will be drawn toward each other by reason of the rods 5 coming in true alinement with each other, thereby spacing said rods from each other equal to the distance or 80 spaces between the slots 7. For the purpose of temporarily holding the credit slip holding leaves together when placed in the position illustrated in Fig. 6 the hooked bar 16 is provided, which hooked bar is pivoted to the 85 rear credit slip holding leaf and the hooked end of said bar passed through the staple 17, connected to the front or forward credit leaf. In some instances it might be desirable to have each credit clip 14 numbered and when 90 this is desired number tabs 18 are attached either to the end flanges 4 or to the ribs 19 or both.

For the purpose of assisting in holding the edges of the credit slips down upon the body 105 or bodies of the various credit slip holding leaves the number tabs 18 are provided with the lateral tangs 20, which lateral tangs are spaced from the faces of the credit slip holding leaves 3 a distance equal to the thickness 110 of the ribs 19 and the width of the end flanges 4, extended at right angles from the faces of the credit slip holding leaves. The credit clips 14 may be substantially of the form shown and as shown they are connected at 115 their bottom or lower ends to the ribs and end flanges of the credit slip holding leaves, preferably by extending the hooked ends 21 into suitable apertures formed in various end flanges or ribs formed upon the credit slip holding leaves. The object and purpose of forming the plates 6 triangular is to allow the bottom or lower edges of said plates to come in parallel alinement with the bottom or lower edges of the credit slip holding leaves, 120 thereby bringing said plates out of the way when the credit slip holding leaves are placed in a safe or other receptacle.

By bringing the lower ends of the credit slip holding leaves parallel with the bases of 125

the triangular plates, the leaves will be brought close together thus saving safe space, but when the bottom or lower ends of the credit slips are located in practical parallel alignment with the hypotenuse lines of the triangular plates 6 they will be spaced the proper distance apart for free and easy action and without any interference one with the other.

10 Having fully described my invention what I claim as new and desire to secure by Letters Patent, is—

1. In a credit cabinet of the class described, a cabinet frame provided with an inclined base, bars carried by said base and pivotally connected thereto, said bars provided with weights located below the base, a series of credit slip holding leaves removably mounted upon the inclined base, and 20 slotted plates pivotally attached to one of the credit slip holding leaves of the series, the remaining credit slip holding leaves being pivotally and slidably connected to the slotted plates, substantially as and for the purpose specified.

2. In a credit cabinet, a cabinet frame, a series of credit slip holding leaves, a support for said credit slip holding leaves secured to the cabinet frame, bars pivotally attached 30 to the support, said bars extended above and below said support, the upper portions of said bars adapted for contact with the credit slip holding leaves, the lower portions thereof provided with weights, and slotted plates 35 pivotally attached to one of the credit slip holding leaves and the remaining leaves of the series pivotally and slidably connected to the slotted plates.

3. In a credit cabinet of the class described, a cabinet frame, a series of credit slip holding leaves provided with rods, said rods provided with rollers, a support for said credit slip holding leaves, weighted bars pivot- 40 ed to the support and adapted to be actuated by the movement of the credit slip holding leaves in one direction, and plates provided with spaced elongated slots, the rods extended through the slots, and said plates pivotally attached to one of the series 45 of credit slip holding leaves, substantially as and for the purpose specified.

4. In a credit cabinet of the class described, a cabinet frame, a series of credit slip holding leaves, a support for said credit slip holding leaves, rods connected to said credit slip holding leaves, and slotted plates, the rods secured to said credit slip holding leaves extending through the slots of the slotted plates, and said slotted plates pivot- 50 ally connected to one of the credit slip hold-

ing leaves, substantially as and for the purpose specified.

5. In a credit cabinet of the class described, the combination of a cabinet frame, said cabinet frame provided with an inclined credit slip holding leaf support, a series of credit slip holding leaves detachably mounted upon the inclined support, slotted plates pivotally attached to one of the series of credit slip holding leaves, the remaining leaves of the series slidably and pivotally connected to said slotted plate, and weighted bars carried by the inclined support and extended above said support, said bars adapted to be actuated in one direction by each leaf 75 of the series of credit slip holding leaves, substantially as and for the purpose specified.

6. In a credit cabinet of the class described, a series of credit slip holding leaves, and triangular plates, each provided with a 80 series of slots of different lengths, said plates pivotally attached to one of the credit slip holding leaves, the remaining leaves of the series being pivotally and slidably connected to the slotted plates, substantially as and for 85 the purpose specified.

7. In a credit cabinet, a series of credit slip holding leaves, plates provided with slots of different lengths, rods secured to the credit slip holding leaves, one of the leaves 90 pivotally attached to the slotted plates, the rods of the remaining credit slip holding leaves located in the slots of the plates, and a catch spring secured to one of the credit slip holding leaves and adapted to engage one of 95 the slots in the slotted plates, substantially as and for the purpose specified.

8. In a credit cabinet a series of credit slip holding leaves, an inclined support for said leaves, plates provided with slots of different 100 lengths, rods secured to the credit slip holding leaves, one of the leaves pivotally attached to the slotted plates, the rods of the remaining credit slip holding leaves located in the slots of the plates, a catch spring se- 105 cured to one of the credit slip holding leaves, and adapted to engage one of the slots in the slotted plates, and weighted arms passing through and pivoted on said inclined support and adapted for contact respectively 110 with the credit slip holding leaves substantially as and for the purpose specified.

In testimony that I claim the above, I have hereunto subscribed my name in the presence of two witnesses.

ROLLO M. VICK.
